Primary Examiner — Messina L Smith*Assistant Examiner* — Elizabeth Borsetti(74) Attorney, Agent, or Firm — Christensen O'Connor Johnson Kindness PLLC(57) CLAIM

The ornamental design for a lip cosmetics container, as shown and described.

DESCRIPTION

FIG. 1 is a front view of a lip cosmetics container in accordance with the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top front right perspective view thereof.

The broken line and the portions therein form no part of the claimed design.
